UNITED STATES PATENT OFFICE.

FRANK F. WOLF, OF BUFFALO, NEW YORK, ASSIGNOR TO RICE & ADAMS CORPORATION, OF BUFFALO, NEW YORK.

BOTTLE-FEEDING MECHANISM.

Application filed January 8, 1923. Serial No. 611,218.

To all whom it may concern:

Be it known that I, FRANK F. WOLF, a citizen of the United States, residing at Buffalo, in the county of Erie and State of New York, have invented a new and useful Improvement in Bottle-Feeding Mechanism, of which the following is a specification.

This invention relates to automatic feed means for feeding articles such as cases or boxes containing milk bottles or the like to a machine such, for instance, as a bottle washing machine. More particularly the feed mechanism embodying the invention is for the purpose of receiving the cases or articles from a conveyor or the like on which they approach the washing machine one in contact with another, and automatically feeding them, one at a time, in spaced relation, so that they may be properly positioned for engagement by the usual feed mechanism of the machine.

In many dairies and similar plants it is customary for the cased bottles to be unloaded from the vehicles directly on to a conveyor or similar transporting device which carries the cases of bottles adjacent to a washing machine. The cases are then removed by hand from the conveyor and placed on a table at the receiving end of the washing machine and pushed into the machine to a position where they may be engaged by the feed device of the machine. This requires that care be exercised in placing the cases in the machine since otherwise the feeding mechanism will fail at times to properly engage a case and so cause delays and ineffectual operation of the machine. The cases cannot be fed directly by the conveyor into the bottle washing machine, as such machines have heretofore been organized, owing to the fact that the cases are fed in on the conveyor in an irregular manner, sometimes touching one another and at other times relatively far apart and at varying distances, so that they would be improperly positioned relatively to the feed mechanism of the machine.

One of the objects of this invention is to provide automatic means for receiving the cases as they are delivered from the conveyor and feeding them, one at a time, prop-

erly timed and in such spaced relation that each one will be positively engaged and carried forward by the feed mechanism of the machine.

Another object is to provide a positive stop for the foremost case on the conveyor, so that the subsequent cases will be arrested by the foremost case, thereby providing a uniform feed of the cases in close array, together with means for disengaging each successive case from the stop and moving it to an intermediate position, and from such intermediate position into proper relation to the mechanism of the machine.

Further objects are to provide a trip device for causing the positive actuation of the automatic feed means.

Other objects are to improve feeding means for machines of this sort in other respects hereinafter set forth and claimed.

In the accompanying drawings:

Fig. 1 is a top plan view of the receiving end of a bottle washing machine, showing one embodiment of the automatic feed mechanism of this invention applied thereto.

Fig. 2 is a longitudinal vertical section on line 2—2, Fig. 1, also showing in broken lines the adjacent parts of a conveyor for feeding the cases to the machine.

Figs. 3 and 4 are views similar to Fig. 2, showing the same parts of the machine in different positions.

Fig. 5 is an elevation of the front end of the machine.

Figs. 6 to 9 are detail figures showing the various operative positions of the trip mechanism for causing the positive actuation of the feed means.

Fig. 10 is a fragmentary sectional elevation of the pusher member of the feed mechanism in an intermediate position.

In the embodiment of the invention disclosed in the drawings the automatic feed mechanism is shown as applied to a bottle washing machine of well known type such for instance as the one illustrated in Letters Patent No. 1,421,055 of June 27, 1922, to Charles S. Adams. This machine includes oppositely disposed fixed guide tracks A, on which the cases rest and on which they are intermittently moved from one operative

position or station in the machine to another, by a reciprocating feed mechanism including opposite finger-supporting bars B having pivoted thereto spaced fingers b which are so positioned that each pair will be caused to move a case one step forward, leaving it at rest on the guide tracks, and then returning to engage the succeeding case and carry it ahead on the next forward stroke. The finger bars may be connected to a cross-head C movable horizontally forward and backward by the usual reciprocating mechanism of the machine (not shown). The guide tracks A are preferably secured to side walls or frame members d with their front ends terminating at some distance from the ends of the side walls.

The means for feeding the cases D to the machine may be of any suitable or usual sort, but is preferably a roller or gravity conveyor as shown at E, having a series of rollers e arranged adjacent the front end of the machine so that the cases will be supported by the rollers and will pass from the conveyor between the walls d. All of these parts have heretofore been used and of themselves constitute no part of this invention.

The frame of the bottle washing or treating machine is provided with a series of oppositely disposed rollers e' arranged on the walls d of the machine in alinement with the rollers e to receive the cases as they leave the conveyor E, these rollers supporting the cases at the sides thereof only, so that the middle portions of the cases may be engaged by the positioning mechanism.

Means are provided for arresting the cases after they are fed onto the rollers e' while they are still some distance from the reciprocating fingers b. The preferred means for this purpose, as shown, comprises a pair of stops 15 which constitute the forward ends of horizontal rails or rests 16 rigidly secured to the frame members d and preferably arranged somewhat higher than the rollers e' and the guide tracks A, so that as a case is pushed over the rollers it will be engaged at its front end, near the bottom, and adjacent its opposite corners by the stops 15, the rear end of this case acting as a stop for the next case, which is about to leave the end of the conveyor E.

The mechanism shown embodying my invention automatically feeds the foremost case from its stop-engaging position, designated as X, where the case may be engaged by the next case, to a position designated as X' where it will be properly positioned for engagement by the first pair of fingers b of the bottle treating machine. While a case is being moved from the position X to the position X', it will occupy two intermediate positions X' X'', the case in the position X' being supported by the rests 16

and in the position X'' the case rests on the guide tracks A ready to be advanced to the position X'. When the mechanism is operating at full capacity, each of these positions will be simultaneously occupied by different cases or crates.

The means preferably employed for lifting the cases from the rollers e' to the rests 16 includes a lifting frame or member 17 which, in the construction shown, has side bars 18 connected by cross bars 19. The ends of the side bars 18 are preferably rounded as shown at 20 so that the lifting frame 17 may enter into the hollow lower ends of the cases or crates to engage the usual bottle-supporting wire bottoms d' of the crates D. The lifting frame is adapted to move up and down with reference to a reciprocatory or horizontally movable slide or carriage which in the construction shown includes a pair of transverse horizontal shafts 22 secured to oppositely disposed, longitudinal slide members 23 resting and adapted to slide on horizontal side guides or tracks 24 secured to the walls d of the machine frame.

Any suitable means may be provided for raising and lowering the lifting frame relatively to the slide or carriage. In the construction shown for this purpose, the lifting frame 17 is provided with depending lugs 25 pivotally connected to arms 27 of a pair of bell cranks 26, one of which is pivoted on each of the shafts 22. The other arms 28 of the bell cranks are pivotally connected to a link 29, so that movement imparted to this link will first cause both bell cranks to swing together on their shafts to cause an up or down movement of the lifting frame 17, and upon further movement of the link 29, the slide or carriage will move longitudinally of the tracks 24.

Any suitable device may be employed for moving the link 29 for the purpose stated, but preferably the reciprocating mechanism which actuates the finger bars B is utilized, by pivotally connecting one end of the link 29 to the cross-head C, as by a connecting rod or pitman 30, which also results in properly synchronizing the movements of the lifting frame 17 with the fingers b of the bars B. In case the positioning mechanism is used in connection with a machine having no reciprocatory feed mechanism, any other suitable means for reciprocating the connecting rod 30 may be used. Upon referring to Figs. 2, 3 and 4, it will be seen that a movement of the cross-head C in the direction of the arrow, or to the right from the position shown in Fig. 2, will impart a swinging motion to the bell cranks 26 resulting first in an upward movement of the lifting frame 17, which will engage and lift the case at X to the position shown in Fig. 3, and the continued travel of the cross-

head C to the right will permit the carriage to move horizontally on the slides 23 to the position shown in Fig. 4, with the case just above the rests 16. The cross-head C 5 has now reached its limit of travel to the right, and upon its initial movement to the left, the bell cranks will first lower the lifting frame 17, leaving the case on the rests 16, and will then pass, while lowered, to the 10 position shown in Fig. 2.

Any suitable means may be provided for limiting the upward movement of the lifting frame relatively to the slidable carriage and for this purpose, in the construction 15 shown, stop members or straps 31 are employed which are secured at their opposite ends to the cross members 19 of the lifting frame and the lower or depending portions of which are adapted to engage collars or 20 parts 32 secured to one of the shafts 22. When the depending portions of the stop members engage the collars 32, all further movement of the connecting rod 29 or pitman 30 to the right in Fig. 3 will result 25 in longitudinal movement of the slide members 23 on the tracks 24. The downward movement of the lifting frame or member relatively to the carriage is limited in the construction shown by means of down- 30 wardly extending flanges 33 of the side bars 18 of the lifting frame, which flanges engage with the slides 23 of the carriage, as shown in Fig. 2.

After a case has been placed on the rests 35 16, the lifting frame 17, as explained, is actuated to engage another case and move it upwardly from the stops 15 and then forwardly and during this forward movement the front of this case engages with the rear 40 of the case on the rests 16 and pushes the latter case off of the rests 16 and onto the guide tracks A. In case the lifting frame carries no case, the front ends of the side bars of the lifting frame will push the 45 case from the rests 16 to the guide tracks.

The means shown for advancing the cases from the position X^2 to the position X^3 preferably comprise a pusher plate or member 34, arranged between the sides of the 50 machine and pivoted on the cross-head C so that the plate will normally assume an inclined position, as shown in Figs. 2, 3 and 4, in which position the front edge thereof extends above the guides and is adapted to 55 engage the rear end of a case at X^2 , when the parts of the mechanism are in the initial position shown in Fig. 2. This plate is pivotally connected to the cross-head C to move horizontally therewith, and consequently 60 when the cross-head C starts moving to the right, the plate 34 will move in the same direction, engaging a case at X^2 and carrying it forward while the first part 65 of the movement of the cross-head C when transmitted to the lifting frame 17, will

cause first a vertical movement thereof through the action of the bell cranks 26, and then a horizontal movement to the right. As a consequence, the case moving from X^2 70 will have a greater horizontal travel than the case moving from X to X' , so that a space will be left between the cases at X^2 and X^3 as shown in Fig. 4. As shown in Fig. 10, the pusher plate 34 on its return stroke will be tilted by its engagement with 75 the case above it so as to permit its passage under the case.

It is also contemplated to provide positively acting means for preventing any horizontal forward or backward movements of the sliding carriage until the lifting frame has first reached its intended upper or lower positions respectively, to ensure the elevating of a case sufficiently to clear the stops 80 15 on the forward stroke of the carriage and to lower the lifting frame before beginning the return stroke. The means shown for this purpose include two pairs of dogs or latches 38 and 39, loosely pivoted at opposite sides of the machine, for instance on the shaft 85 22. The latches 38 extend downwardly towards the right, with their outer ends adjacent to or contacting with fixed stop bars 40, see particularly Figs. 6-9. In the initial 90 position, Figs. 2 and 6, the ends of the latches 38 abut against stops or shoulders 41 on the bars 40, preventing movement of the lifting frame 17 to the right, until the latches are released. Lugs 42 on the latches 95 38 are so positioned that when the lifting frame has moved upwardly to the proper extent, these lugs 42 will be engaged to swing the lower ends of the latches free of the stops 41 and permit the forward movement of the carriage. Any suitable trip device 100 may be used for this purpose, such as sleeves 43 loosely surrounding the shaft 22 on which the latches are pivoted, and having extending fingers 44 adapted to rotate in the path of the lugs 42, the sleeves being 105 suitably connected with the bell crank 26 and movable therewith. The fingers 44 are so positioned that they will rotate without engaging the lugs 42 until the carriage approaches its upward limit, when the latches 110 115 will be tripped as explained, and held by the fingers out of contact with the stop bars until the carriage reaches its farthest right-hand position as shown in Fig. 4. During 120 this operation the other pair of latches 39 will slide freely over the stop bars and their ends will drop into place in engagement with stops 46, see Figs. 4 and 9. These latches are similarly actuated by a rotation of the fingers 44 in an opposite direction to 125 permit their release when the lifting frame 17 reaches its lowest position previous to its travel to the left. Any other suitable device may be used to positively hold the carriage against horizontal movements until 130

it has made the proper vertical movements for the purpose stated.

The mechanism described is of simple form and an inexpensive addition to machines of the sort mentioned. It is sturdy in construction and positive in operation and not liable to get out of order, and the described connections between the cross-head and the feed mechanism ensures a proper cooperation of the feed positioning mechanism with the bottle treating machine.

I claim as my invention:

1. The combination with a bottle treating machine having a feed device for passing cases of bottles through the machine, and a conveyor for supplying cases of bottles to said machine, of a stop against which the cases are placed by said conveyor, and mechanism for moving said cases out of engagement with said stop and into operative relation to said feed device, said case-moving mechanism being adapted to simultaneously move a case from said stop to an intermediate position between said stop and said feed device, and discharge another case from said intermediate position to another position in which it will be engaged by said feed device.

2. In an article feeding and positioning mechanism, the combination with means for supplying articles successively to a starting position with reference to said mechanism, and a machine having a reciprocating feed device to which said articles are to be fed, of an initial article-advancing device adapted to first elevate an article and then advance the same, connections between said reciprocating feed device and said initial advancing device which cause a part of the reciprocating motion to be translated into motion for elevating the article, and a second advancing device which reciprocates with said feed device, whereby said second advancing device advances the article to a greater extent than said initial advancing device to space the articles at intervals.

3. In an article feeding mechanism, the combination with means for supplying articles successively to a starting position with reference to said mechanism, of a reciprocating carriage movable below said articles, a frame mounted on said carriage and adapted to move up and down relatively to the carriage to engage an article and lift the same, an arm connected with said carriage and adapted to be swung to actuate said frame, a reciprocatory member connected with said arm for swinging the same to a limited extent to effect the up and down movement of said frame and to cause said carriage to reciprocate after the up and down movement of the frame is completed, and means for holding said carriage against reciprocatory movement during the up and down movement of said frame.

4. In an article feeding mechanism, the combination with means for supplying articles successively to a starting position with reference to said mechanism, of a reciprocating carriage movable below said articles, a frame mounted on said carriage and adapted to move up and down relatively to the carriage to engage the article in the starting position and lift the same, an arm connected with said carriage and adapted to be swung to actuate said frame, a reciprocatory member connected with said arm for swinging the same to a limited extent to effect the up and down movement of said frame and to cause said carriage to reciprocate after the up and down movement of the frame is completed, dogs mounted on said carriage and adapted to hold said carriage against reciprocatory movement while said frame is being moved up and down, and means connected with said arms for releasing said dogs when said frame has completed its up and down movement.

5. In an article feeding mechanism, the combination with means for supplying articles successively to a starting position with reference to said mechanism, of a reciprocating carriage movable below said articles, a frame mounted on said carriage and adapted to move up and down relatively to the carriage to engage the article in the starting position and lift the same, a pair of bell cranks pivotally mounted on said carriage and each having an arm connected with said frame for effecting the up and down movement thereof, means for limiting the up and down movement of said frame relatively to said carriage, reciprocatory means connected with said bell cranks for causing the same to swing about their pivots to effect the up and down movement of said frame and to impart reciprocatory movement to said carriage, and means for holding said carriage against reciprocatory movement until said frame has completed its up and down movement.

6. The combination with a machine for treating bottles in cases, said machine having reciprocating feed means for passing said cases therethrough, and a conveyor for delivering said cases in contact, one behind the other to said machine, of a stop for successively arresting the cases as they are discharged from said conveyor, a fixed support adjacent to and beyond said stop, and means for successively lifting said cases away from said stop and depositing them on said support and then moving them from said support to a position to be engaged by said reciprocating feed means.

7. The combination with a machine for treating bottles in cases, said machine having reciprocating feed means for passing said cases therethrough, a guide on which the cases are supported during their passage

through said machine, and a conveyor for said cases away from said stop and depositing them on said fixed support, and then delivering said cases in contact, one behind the other to said machine, of a stop for successively arresting the cases as they are discharged from said conveyor, a fixed support arranged beyond said stop and in advance of said guide, and means for lifting

said cases away from said stop and depositing them on said fixed support, and then moving them to a position on said guide 10 wherein they are adapted to be engaged by said reciprocating feed means.

FRANK F. WOLF.
